UNITED STATES PATENT OFFICE.

LEWIS F. WHITE, OF POND, WEST VIRGINIA.

PLANTER.

1,382,945.

Specification of Letters Patent. Patented June 28, 1921.

Application filed May 15, 1920. Serial No. 331,670.

To all whom it may concern:

Be it known that I, LEWIS F. WHITE, a citizen of the United States, residing at Pond, in the county of Boone and State of West Virginia, have invented certain new and useful Improvements in Planters, of which the following is a specification, reference being had to the accompanying drawings.

10 This invention relates to certain improvements in planters, and it is an object of the invention to provide a novel and improved device of this general character wherein the dropping mechanism embodies a reciprocating member or shutter coacting with a plurality of hoppers, preferably two in number, and whereby the seeds from within each of the hoppers may be dropped.

15 It is also an object of the invention to provide a novel and improved device of this general character embodying a wheel supported beam having mounted thereon a plurality of hoppers, together with means coacting with said hoppers and operable from the supporting wheel to drop the seeds within the hoppers.

The invention consists in the details of construction and in the combination and arrangement of the several parts of my improved planter whereby certain important advantages are attained and the device rendered simpler, less expensive and otherwise more convenient and advantageous for use, as will be hereinafter more fully set forth.

20 35 The novel features of my invention will hereinafter be definitely claimed.

In order that my invention may be the better understood, I will now proceed to describe the same with reference to the accompanying drawings, wherein:

Figure 1 is a view in side elevation, illustrating a planter constructed in accordance with an embodiment of my invention;

Fig. 2 is an enlarged fragmentary sectional view, illustrating in detail the reciprocating shuttle or piston and the means for operating the same; and

Fig. 3 is a fragmentary sectional view taken substantially on the line 3-3 of Fig. 2.

As disclosed in the accompanying drawings, B denotes a beam of requisite dimensions and which is provided at one end with a clevis 1, or the like, whereby suitable draft rigging may be hitched thereto. In the present embodiment of my invention, I dis-

close a device which is particularly adapted to be drawn by a single draft animal although I do not wish to be understood as limiting myself in this respect.

Secured to the rear portion of the beam B and extending laterally therefrom is a frame F and rotatably supported by the outer side member 2 of the frame F and the adjacent portion of the beam B is a transversely disposed shaft 3. Fixed to the shaft 3 within the frame F is a ground engaging or supporting wheel W, of desired diameter. Also fixed to the shaft 3 at a desired distance inwardly of the wheel W is a trip wheel or member 4 having produced in its peripheral portion a plurality of circumferentially spaced openings 5 in each of which is adapted to be threaded a trip member or finger 6. The members or fingers 6 may be readily applied or removed as the occasions of practice may require.

Supported by the beam B is a cylinder C extending longitudinally thereof and which is provided in its under wall at substantially its center with a relatively large opening 7 having its side portions defined by the outstanding flanges 8.

Arranged upon the cylinder C is a hopper H, with the upper portion of the wall of the cylinder C constituting the bottom of said hopper. The lower side marginal portions of the hopper H are defined by the outstanding flanges 9, resting upon the flanges 8 and bolted or otherwise secured thereto. The hopper H is further maintained in applied position by the stays 10 bolted or otherwise secured both to the beam B and the walls of the hopper H. The hopper H is divided into two compartments, x and y, by a substantially central partition 11 and the upper wall of the cylinder C is provided with a pair of openings 12, each of which being in communication with one of the compartments x or y.

Snugly fitting within the cylinder C and having rectilinear or reciprocatory movement therein is a hollow shuttle or piston 14 having its inner end portion closed by a head 15. Engaged with the outer end portion of the piston or shuttle 14 is a bolt or lug 16 depending through a slot 17 extending longitudinally of the lower wall of the cylinder C and which bolt or lug is of a length to intersect the path of travel of the members or fingers 6 so that said piston or shuttle will be intermittently moved in-

wardly upon rotation of the trip wheel or member 4. The piston or shuttle 14 is constantly urged in the opposite direction through the instrumentality of the expansive member or coil spring 18 interposed between the head 15 and the adjacent head 18 of the cylinder C. The upper wall of the piston or shuttle 14 is provided with a pair of longitudinally spaced openings 20 which, when the piston or shuttle 14 is at the limit of its inward movement by contact of a finger 6 with the lug 16 registers with the openings 12 so that the seeds within the compartments α and γ will enter within the shuttle or piston 14 and will drop through the opening 7.

Underlying the opening 7 is the enlarged upper end portion 21 of a seed chute S and the upper side margins of said portion 21 of the chute S are defined by the outstanding flanges 22 which are also secured to the flanges 8. The lower portion 23 of the chute constitutes a tube which leads to and terminates in close proximity to a lister plow P, operatively supported by the beam B. Extending upwardly and rearwardly from the beam B and the outer side member 2 are the handle members 24 of a conventional type. Coacting with each of the openings 12 is a regulator plate 25 having one end portion extending exteriorly of the hopper H. Said extended portion of the plate 25 is provided with a longitudinally disposed slot 26 through which is disposed a clamping screw 27 in threaded engagement with the adjacent wall of the cylinder C. The plate 25 is adapted to have its inner end portion adjusted with respect to the adjacent opening 12 so that the feed through the opening 40 may be varied as may be required and the clamping screw 27 operates to maintain said plate fixed in its desired adjustment.

In practice, the compartments α and γ are each adapted to contain a particular kind of seed, such as seed corn in one compartment and bean seeds in the second compartment, as the device is particularly adapted to plant corn and beans at the same time. When required, either of the openings 12 may be closed by its coacting and regulator plate 25 so that only one kind of seed will be dropped.

It will also be understood that by removing certain of the fingers or members 6, the space between the hills may be varied as best meets the requirements of practice.

From the foregoing description, it is thought to be obvious that a planter constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:—

A planter including a cylinder having an opening in its lower wall, the upper portions of the opening being defined by outstanding flanges, a hopper imposed upon the cylinder, the top wall of the cylinder constituting the bottom of the hopper, said hopper being provided with outstanding flanges overlying the flanges of the cylinder, means for securing said overlying flanges together, the bottom of the hopper being provided with an opening affording communication between the interior of the hopper and the interior of the cylinder, a tubular shuttle movable within the cylinder, means intermittently moving the tubular shuttle in one direction, automatic means for moving the shuttle in the opposite direction, said shuttle being provided with an opening in its wall to register with the opening in the bottom of the hopper when the hopper is moved in one direction by the first named means, said opening of the shuttle being out of register with the opening in the bottom of the hopper when at the limit of its movement by the automatic means, said shuttle being provided with a second opening registering with the discharge opening in the lower wall of the cylinder.

In testimony whereof I hereunto affix my signature.

LEWIS F. WHITE.
